ROLLER WINDOW SCREEN

Edward M. Hoover, Anderson, Ind.

Application February 17, 1942, Serial No. 431,285

3 Claims. (Cl. 160—242)

This invention relates to a roller window screen and has for its primary object a screen carried by a spring roller and operatively attached between the usual form of window casing and the slideable sash thereof for the purpose of automatically positioning the screen covering the opening of varying sizes when the window is moved to its open position in the window frame.

A further object of the invention is the provision of a window screen normally mounted upon a roller whereby the screen is automatically extended during the window opening operation and re-rolled upon the roller out of use when the window is returned to its closed position.

A still further object of the invention is to provide an automatically operated window screen adapted for use with any width of window and being of simple construction and inexpensive to manufacture as well as serviceable and advantageous wherever a window screen is required, and having adjustments furnished to accommodate different lengths of window screen ready for use and detachably mounted upon the window frame.

With these general objects in view and those that will appear as the nature of the invention is better understood, the invention consists of the combination and arrangement of parts hereinafter fully described in connection with the accompanying drawing and then pointed out in the appended claims.

In the drawing:

Figure 1 is an elevational view of a window frame having the usual sliding sash and with my automatic window screen mounted thereon, the window being in a partially open position;

Figure 2 is a slightly enlarged vertical sectional view taken upon line 2—2 of Figure 1, and looking in the direction of the arrows;

Figure 3 is a similar enlarged sectional view taken upon line 3—3 of Figure 1, and likewise being enlarged and with parts broken away;

Figure 4 is an enlarged sectional view taken through the lower portion of the sash in its closed position with the automatic window screen entirely rolled upon its spring roller.

Referring more in detail to the drawing, there is illustrated the usual form of rectangular window frame having opposite sides 10 and bottom 11 with the window sill 12 carried by and forming a part of the bottom of the window frame.

The window sash 13 is vertically slideable in the window frame and provided with oppositely positioned removable retaining strips 14 normally overlying the opposite edges of the sash 13.

which is thereby operatively mounted for use in the frame 10 although manually removable at will.

The gist of my invention consists of a screen 15 which may be of fabric or metal or any material desired having the necessary foraminous body structure and with one end of the screen 15 secured to the lower rail 16 as by hold-fast devices 17 passing through a binding 18 permanently attached to one end of the screen 15. The opposite end of the screen 15 is attached to the spring operated roller or barrel 19 whereby the coil spring 20 is mounted within said barrel 19 and automatically rewinds the window screen 15 during the closing of the sash opening 20. The screen 15 may be made of impregnated weather-proofed material.

The most material feature of the invention is the manner of mounting the automatic roller 19 to the screen 15 upon the window frame 10 and this is accomplished by a pair of attaching brackets 21 secured to the opposite inner faces 22 of the window frame 10.

The mounting brackets 21 are adjustable in height, made possible by the attaching screws 23 passing through the brackets 21 and into the adjacent face 24 of the window frame 10, as best illustrated in Figs. 2 and 4 of the drawing. The position of the attaching brackets 21 is regulated when mounting the roller screen 15 upon the window frame 10 and being so arranged that the complete window screen 15 may be accommodated wound upon the spring roller 19, as shown in Figure 4 of the drawing.

An idler roller 25 has end trunnions 26 for revolvably mounting the idler 25 in the brackets 21 with said idler roller 25 in parallelism with spring actuated mounting roller 19.

The complete operation of the device will be at once apparent from this detailed description thereof, it being understood that with the screen 15 having one end attached to the lower edge or rail of the slideable sash 13, that the opening of the sash 13 pulls upwardly on the screen 15 unwinding the same from the spring roller 19 substantially covering the opening 20 of the window frame. Upon closing the sash 16 by lowering the same, the spring 20 of the automatic roller 19 rewinds the screen 15 upon said roller 19 after the manner of a window shade or other spring mounted automatically operated roller.

It will be apparent that by releasing the set screws 23 for the brackets 21 that the relative positions of the roller 19 and roller 25 may be made to accommodate different forms of window

screen as well as to accurately adjust the mounting bracket 21 to accommodate the screen 15 when completely rewound upon the spring roller 19 with the window sash 16 in its lowered closed position.

While the form of the invention herein described and illustrated is believed to be the preferable embodiment of the invention, it will be understood that minor changes can be made in the form proportions and details of construction without departing in any manner from the spirit and scope of my invention.

I claim:

1. In a roller window screen of the character described, a mounting bracket adjustably secured to a side of a window frame adjacent the lower end thereof, a screen roller and a guide roller for the screen journaled at one end in said bracket, the adjustable mounting for said bracket including a screw between the ends thereof about which the bracket may be held to position the axis of the screen roller at a greater distance from the window sill than the maximum radius of the screen wound on the screen roller.

2. In a roller window screen of the character

described, a mounting bracket adjustably secured to a side of a window frame adjacent the lower end thereof, a screen roller and a guide roller for the screen journaled at one end in said bracket, the bracket comprising a plate having end flanges for engaging the adjacent side of a window frame and provide projection space for the journal pins of the screen and guide rollers.

3. In a roller window screen of the character described, a mounting bracket adjustably secured to a side of a window frame adjacent the lower end thereof, a screen roller and a guide roller for the screen journaled at one end in said bracket, the adjustable mounting for the bracket including a screw between the ends thereof about which the bracket may be pivoted to position the axis of the screen roller at a greater distance from the window sill than the maximum radius of the screen wound on the screen roller, the bracket comprising a plate having end flanges for engaging the adjacent side of the window frame to space the plate from the window frame and provide projection space for the journal pins of the screen and guide rollers.

EDWARD M. HOOVER.
